UNITED STATES PATENT OFFICE.

ERNESTO ZOLLINGER, OF TURIN, ITALY.

PROCESS FOR REDUCING THE SIZE OF PICTURES ON KINEMATOGRAPH-FILMS AND OF PROJECTING SUCH PICTURES TO THEIR NORMAL PROPORTIONS.

1,032,172.

Specification of Letters Patent.

Patented July 9, 1912.

Application filed March 22, 1910. Serial No. 550,915.

To all whom it may concern:

Be it known that I, ERNESTO ZOLLINGER, a citizen of Switzerland, residing at Turin, in the Kingdom of Italy, have invented a new and useful Process for Reducing the Size of Pictures on Kinematograph-Films and of Projecting such Pictures to Their Normal Proportions, of which the following is a specification.

Kinematograph films at present in use generally consist of celluloid bands or ribbons having a width of about 35 mm. and a forward movement of about 19 mm. and the size of the pictures on them is usually 25 mm. in width and a height equal to the forward movement of the band, namely 19 mm. These films are long and expensive, and there is no other practical way of reducing their cost than that of reducing the size of the individual pictures upon the films, since any reduction of the films in width, or the extent of their movement would entail a change, or rather an important modification of the machines now in use, which it is naturally desirable to avoid.

The present invention has for its object a reduction of the size of the pictures on the kinematograph films by a simple and inexpensive process, but which realizes perfectly the object desired to be attained.

By my method it is possible to obtain a reduction to one-half the width or height without producing the least diminution of clearness in the projection. It is possible to obtain this reduction of the pictures to one-half the size in two ways: 1. The picture on the film is reduced to one-half the size, namely 25 mm. by 9.50 mm. by reducing its width. 2. The picture on the film is reduced to one-half the size, namely 12.50 mm. by 19 mm. by reducing its height.

In both cases the size and shape of the projected picture when used in machines as used at present would no longer be in proportion to the customary projections, as it would only cover one-half of the field on the screen, either vertically or horizontally. This is avoided in my invention by employ-

ing an ordinary deformer such as is well known and used in photography, the deformation being produced either by cylindrical lenses or by one or several prisms combined. The procedure is as follows: In the first place the deformer is inserted into the optical system of the machine employed for taking the pictures. It is, of course, possible to reduce the pictures to any dimensions, but for the reasons previously stated, a deformer will be chosen giving just a half reduction of one of the sides relatively to the other. According to the arrangement given to the deformer in this machine there will be obtained a deformation in height (vertical) or in width (horizontal) of the picture, that is to say a reduction to one-half its area without in any way diminishing the photographic field, *i. e.* the amplitude of the scene which it is desired to reproduce. These pictures thus deformed when developed and the positives made therefrom, will be projected by employing the same or a like deformer, said deformer added to the objective of the projecting apparatus, thus producing an inverse and equal deformation to the original one, and consequently obtaining on the screen projected pictures of the normal size and undeformed.

In the accompanying drawing—Figure 1 shows an ordinary film, Fig. 2 shows a negative film obtained in accordance with the present invention, where the deformed pictures have been reduced to one half their height, and Fig. 3 shows a corresponding positive film.

In the case referred to in which the pictures occupy a space 25 mm. by 9.50 mm., their arrangement on the film, will be as follows: The forward movement of the film in cameras at present in use being about 19 mm. that is to say, double the height of the pictures, it will be necessary to employ a shield or screen of one-half the usual height, so that there will remain upon the negative film, between each two consecutive pictures, depicted by the hatching *a*, an empty space

b (Fig. 2), that is to say, an interval not exposed, of the same height as the pictures themselves.

The positive film (Fig. 3) is then made 5 from one, two, or several such negatives. First one of these negatives is printed by an apparatus having a forward movement of 19 mm. after having modified the frame to the height of the negative image. Then the 10 positive film is displaced relatively to the negative a distance equal to one-half its travel, (two holes, for there are usually four holes in the total height of the picture of an ordinary film,) and the second part of the 15 negative is printed upon the empty spaces or intervals not exposed, either reversed or in the same direction.

The projecting apparatus moves this 20 printed positive film the normal distance for each exposure, *i. e.*, double the height of a picture on it, and will be provided with a corresponding shield or screen, so that in the first operation the pictures *a* having odd numbers will be projected on the screen, and 25 in the second operation those having even numbers designated *c* in Fig. 3 will be projected, or vice versa, and according to one or both of the cases indicated the projections of the two series (generally two different 30 scenes) will commence either at the same end of the film or at opposite ends.

If it were desired to have the pictures of one scene consecutive on the film, it would be necessary to change, reduce to half, the 35 amount of movement upon all projecting machines if the existing system of perforation be retained, or to adopt a new system of perforation in conformity to the reduced height of the pictures on the new films, for 40 example, one hole for each picture on each side, that is to say a system of perforation in which the holes are double the distance apart of those now in use.

In the second case above indicated in 45 which the pictures are reduced to one-half width, namely 12.50 mm. by 19 mm. the negatives are copied on the longitudinal half of the film, right or left. Thus a positive film is obtained by printing the two halves 50 of the negative over the two longitudinal halves of the positive film, reversed in direction or not, as desired. There will thus be obtained on the same film two columns of pictures, representing generally two different 55 scenes. This fact sometimes presents inconveniences, especially when selling or lending films, as it causes an increase in price, so that it is desirable not to have two columns of pictures upon the same film, 60 as in the case above described. This is remedied by cutting these positives longitudinally into two on their median line forming the vertical separation of these two scenes. Thus two positives are obtained,

each of one-half width, furnished with a 65 single row of perforations on only one of their sides. The projection of these narrow bands will be facilitated by the employment of guides in the place of the missing half.

To economize time in the making of these 70 films it is advantageous to make a counter type negative, that is to say, to print, in the manner indicated, a positive regular in density and complete. From this first positive a second negative is made which is now 75 double and of uniform density. With this double negative (which can be divided into parts according to the size of the developing frames or according to the manner employed for developing,) definite positives are made 80 exactly as with a simple negative with the advantage of printing two pictures at the same time and without requiring to change the light after each part.

Finally, it is to be remarked that ordinary 85 negatives can be utilized, such as are obtained by old methods, in conjunction with the present invention, by inserting during the exposure between the said negatives and the positives being exposed the same deformer or reducer used in taking pictures in the present process.

In lieu of deforming the picture on the negative by the reduction to one-half of one of its sides, the contrary method of working may be used, that is to say, to employ in the machine for taking the pictures an object glass capable of giving with the same photographic field a picture having both sides half the dimensions of ordinary pictures, in combination with a deformer enlarging only one of the two sides, either the horizontal or the vertical side. There will thus be obtained a negative identical with that obtained in the manner above described. 10 The rest of the procedure remains unvaried.

I claim—

1. The art of producing moving pictures, which comprises deforming the picture on the film by reducing one of its dimensions to a fraction thereof and projecting the deformed picture through a deformer to reconstruct the projection to normal proportions.

2. The art of producing moving pictures, which comprises deforming the picture on the film by reducing its vertical dimension to a fraction of its height without reducing the optical field, and projecting the picture through a deformer to reconstruct the projection to normal proportions.

3. The art of producing moving pictures, which comprises deforming the pictures on the film by reducing their vertical dimension to a fraction of their height 11 without reducing the optical field and without reducing the travel of the film, thereby forming a series of pictures having in-

terspaces between the individual pictures on the film and producing a similar series of deformed pictures in said interspaces, and projecting the pictures through a deformor 5 to reconstruct the projection to normal proportions.

4. In the art of projecting moving pictures, a film having pictures thereon deformed to reduce one of their dimensions to

a fraction of the same dimensions of the normal picture.

In witness whereof I have hereunto set my hand in presence of two witnesses.

ERNESTO ZOLLINGER.
